UNITED STATES PATENT OFFICE.

PERCY I. ANSORGE, OF NEW YORK, N. Y.

DESIGN FOR A LIGHTING-FIXTURE BRACKET.

Application filed September 12, 1924. Serial No. 10,766. Term of patent 7 years.

To all whom it may concern:

Be it known that I, PERCY I. ANSORGE, a citizen of the United States, residing at #320 Eastern Parkway, in the county of Kings, borough of Brooklyn, city and State of New York, have invented a new, original, and ornamental Design for a Lighting-Fixture Bracket, of which the following is a specification, reference being had to the accompanying drawing, forming part thereof.

I claim:

The ornamental design for a lighting fixture bracket, substantially as shown.

PERCY I. ANSORGE.
